UNITED STATES PATENT OFFICE.

CARL A. RIETZ, OF SAN FRANCISCO, CALIFORNIA.

DESIGN FOR A LIQUID-AGITATING MACHINE.

59,683.

Specification for Design.

Patented Nov. 15, 1921.

Application filed March 22, 1920. Serial No. 367,884. Term of patent 14 years.

To all whom it may concern:

Be it known that I, CARL A. RIETZ, a citizen of the United States, and a resident of the city and county of San Francisco, State of California, have invented a new, original, and ornamental Design for a Liquid-Agitating Machine, of which the following is a specification, reference being had to the accompanying drawing, forming part thereof.

The figure is a perspective view of a liquid-agitating machine, showing my new design.

I claim:

The ornamental design for a liquid-agitating machine substantially as shown.

In testimony whereof I have hereunto set my hand at the city and county of San Francisco, State of California, this 13th day of March, 1920.

CARL A. RIETZ.
